Letters Patent No. 77,495, dated May 5, 1868.

IMPROVEMENT IN WOOD-TURNING LATHES.

The Schedule referred to in these Letters Patent and making part of the same.

TO ALL PERSONS TO WHOM THESE PRESENTS MAY COME:

Be it known that I, SAMUEL U. KING, of Windsor, of the county of Windsor, and State of Vermont, have made a new or improved Machine for Rounding Crooked or Tapered Sticks; and I do hereby declare the same to be fully described in the following specification, and represented in the accompanying drawings, of which—

Figure 1 denotes a front view, and

Figure 2 a rear view of it.

Figures 3 and 4 are transverse sections of it, taken in planes at right angles with each other and through the axis of the machine.

In such drawings, A denotes a wheel provided with two tubular journals, B C, fastened to and projecting from opposite sides of the body of such wheel.

Within a groove extending diametrically across the wheel are two slides, D D, which I term centralizers, they being arranged on opposite sides of the axis of the wheel.

Four curved levers, E E E E, are arranged against one side of the wheel, in manner as represented in fig. 1, they being secured to the wheel by screws $a a a a$, which go through them; and screw into the wheel and constitute fulera for the levers. A pair of these levers is pivoted to each of the centralizers, D D. The longer arms of both pair of the levers extend through two weights, F F, arranged to slide freely in guides or a groove disposed at right angles with the grooves in which the centralizers are placed.

Another pair of centralizers, G G, with levers H H and weights I I, corresponding with the hereinbefore-mentioned centralizers, levers, and weights, is similarly applied to opposite sides of the wheel, and so that the second pair of centralizers may stand at right angles with the first.

To the outer sides of the centralizers G G, turning-cutters K K are affixed, each being made to project a little distance beyond the inner end of the centralizer to which it is attached.

Figure 5 is a side view, and

Figure 6 an edge view of one of the said centralizers and its cutter.

One cutter will be sufficient for the machine, but I prefer two of such cutters, that is, one to each of the pairs, as in that case the cutting or rounding of the stick will be done to better advantage.

The machine so made is to be supported in boxes, applied to its journals, the whole being so as to enable a wheel to be put in revolution by a driving-belt applied to the periphery thereof.

When the machine is in revolution, the slide-weights, by the action of centrifugal force, will be thrown outward from the axis of the wheel, and consequently, by acting on the longer arms of the levers, will turn such levers, and force the centralizers inward toward the centre or axis of the wheel, and so as to keep them in contact with any article which may extend between them.

Thus, when a stick is forced between the inner ends of the four centralizers, they will centralize it with reference to the cutters, which, as the stick may be pushed longitudinally forward, will round it, no matter how crooked or tapering the stick may be, so long as it can be forced through the bores of the journals of the wheel. While the centralizers centralize the stick with respect to the cutters, they will be kept firmly up to it by the action of the weights and the levers.

This machine has been found to be of great service in rounding scythe-snath blanks and various other sticks.

The machine may be constructed with three centralizers, provided with one or more cutters, and with weights and levers to operate the centralizers in manner as described, in which case the centralizers are to stand at angles of one hundred and twenty degrees, instead of at angles of ninety degrees with each other.

What I claim as my invention is—

The combination of the centralizers, their levers and centrifugal weights, with one or more cutters, and a wheel having tubular journals, or the equivalents thereof, the whole being arranged substantially in manner and so as to operate as and for the purpose hereinbefore described.

SAMUEL U. KING.
